UNITED STATES PATENT OFFICE.

FRANK PERLEY HARTLEY, OF BANGOR, MAINE.

AUTOMATIC ALARM.

Application filed October 23, 1922. Serial No. 596,366.

To all whom it may concern:

Be it known that I, FRANK PERLEY HARTLEY, a citizen of the United States, residing at Bangor, in the county of Penobscot and 5 State of Maine, have invented certain new and useful Improvements in Automatic Alarms; and I do declare the following to be a full, clear, and exact description of the invention, such as will enable others skilled 10 in the art to which it appertains to make and use the same.

My invention relates to improvements in automatic alarms and more particularly to those operated by a thermostat, for the purpose 15 of sounding an alarm in case of fire.

The object of the invention is to provide an extremely simple and effective, yet a highly efficient and reliable device for obtaining the necessary results.

With the foregoing in view, the invention resides in the novel subject matter herein-after described and claimed, the description being supplemented by the accompanying 20 drawings:—

Figure 1 is a top view partly in horizontal section.

Fig. 2 is a bottom plan.

Fig. 3 is a vertical section on line 3—3 of Fig. 1.

Fig. 4 is a side elevation with the casing door opened.

Fig. 5 is a horizontal section on line 5—5 of Fig. 4.

In the construction here disclosed, the 35 numeral 1 designates a casing having an opening 2 occupying the greater part of the area of its bottom, said opening however, being substantially closed by a disk-like thermostat 3. The entire casing is preferably 40 constructed of metal or other fire-proof material and the thermostatically controlled means for sounding an alarm in case of fire, are located for the most part within said casing, a suitable door 4 being provided so that access to the internal parts may be had whenever desired.

In the present showing, I have illustrated a spring motor 5 within the casing for operating a bell clapper 5' which extends 50 through the casing top for coaction with a bell 6. Operation of this clapper however is normally prevented by an alarm control lever 7 which is fulcrumed at 8 upon a post 9 which rises from the casing to carry the 55 bell 6. The lever 7 is passed downwardly through an arcuate slot 10 in the top of the

casing, as indicated at 11, then extends horizontally in one direction as indicated at 12, is next directed horizontally at right angles as shown at 13, and terminates in a free end 14 parallel with the portion 12. This lever terminal 14 normally is held by a nose 15 on a vertically movable latch lever 16 which is fulcrumed between its ends at 17 on a supporting arm 18 which depends from the casing top. This arm is provided with a finger 19 which normally engages the lever end 14 to prevent the latter from accidentally springing away from the nose 15. As soon as this nose releases the lever 7, the latter 70 is moved by a coiled spring 20, so that it in turn releases the bell clapper 5', permitting the latter to come into operation.

At this point, it may be stated that instead of using the spring motor on the parts 75 5' and 6, I might rely upon the lever 7 striking a contact (not shown) to complete an electrical circuit for the purpose of sounding an alarm.

The end of the latch lever 16, remote from 80 its nose 15, is provided with a tubular guide 21 which is pivoted thereto by means of a set screw 23 which extends to the interior of said guide for the purpose of clamping a latch releasing needle 24 in adjusted position in said guide. This needle engages a seat at the center of the thermostat 3 and it will thus be seen that after proper adjustment of said needle, expansion of the thermostat under heat, will cause the lever 16 90 to release the control lever 7, thereby effecting sounding of the alarm.

As excellent results have been obtained from the details disclosed, they are preferably followed, but within the scope of the 95 invention as claimed, numerous minor changes may be made.

I claim:—

1. An automatic alarm comprising a support, a thermostat carried thereby, alarm means, an alarm control element carried by said support and preventing operation of the alarm when in a set position, means yieldably holding said control against movement to a set position, a latch movably carried by said support for engaging said alarm control and releasably holding the alarm control in a set position, and means connecting said latch with said thermostat for permitting operation of said latch by 110 said thermostat.

2. An automatic alarm comprising a cas-

ing having a slot in one side, a bracket in the casing spaced from said slot, alarm means, an alarm control lever extending through said slot and fulcrumed upon the casing, and yieldably held against movement into a set position, said lever when in a set position preventing operation of the alarm means, a latch pivoted on said bracket for normally holding said lever against movement out of a set position, a thermostat at one side of the casing, and a releasing device pivoted to said latch and engaging said thermostat.

3. An automatic alarm comprising a support carrying a thermostat, alarm means, an alarm control pivoted on said support, and yieldably held against movement to a set position, the alarm control when in a set position preventing operation of the alarm, a latch lever fulcrumed on said support and having a nose normally engaging said control to hold the control in a set position, a guide pivoted to said latch lever, and a releasing needle adjustably held in said guide and engaging said thermostat.

4. An automatic alarm comprising a casing having an opening in its bottom and a thermostat substantially closing said opening, a bell mounted on the upper side of said casing, a bell clapper extending through the casing top and a spring motor in the casing to operate said clapper, a lever fulcrumed on the casing and when in an operative position engaging said clapper to hold the same against operation, spring means engaging said lever for moving the lever out of an operative position, said lever extending downwardly through an opening in the casing top and having a horizontally directed inner end, a bracket arm within the casing extending from one side thereof, a vertically swinging latch lever fulcrumed on said bracket arm and normally engaging said first named lever to hold the latter against movement by said spring and a releasing device extending from the other end of said latch lever to said thermostat.

In testimony whereof I have hereunto affixed my signature.

FRANK PERLEY HARTLEY.
